UNITED STATES PATENT OFFICE.

FREDERICK C. FARNSWORTH, OF BROOKLYN, NEW YORK.

COMBINED RECEIVING-TANK AND PUMP-GOVERNOR.

1,216,427.

Specification of Letters Patent.

Patented Feb. 20, 1917.

Application filed March 23, 1915. Serial No. 16,505.

To all whom it may concern:

Be it known that I, FREDERICK C. FARNSWORTH, a citizen of the United States, and resident of Brooklyn, county of Kings, and 5 State of New York, have invented an Improvement in Combined Receiving-Tanks and Pump-Governors, of which the following is a specification.

My invention relates to means for collecting 10 and measuring water, and which is also adapted to operate to control its delivery.

The object of my invention is to provide a suitable collecting and delivery apparatus for water of condensation or feed water, 15 which shall be positive in action, rapid in operation, and free from all delicate mechanism, stuffing boxes, packing or small controlled passages, which are liable to clog or otherwise prove defective. It has for a further object to provide an apparatus for 20 measuring the water handled either under pressure or by gravity, said operation of measuring being positively and accurately accomplished and registered automatically 25 as the water is delivered by the apparatus during its operation.

It has for a further object to provide a pump governing mechanism controlled and regulated by the water to be handled, where- 30 by the pump may be operated commensurately with the presence of the water collecting, the water being automatically pumped at intervals from the collecting apparatus to a boiler or other receptacle.

35 My invention also comprehends the features of construction for accomplishing the above specified objects, said construction being fully described hereinafter and defined in the claims.

40 In the drawings: Figure 1 is a plan of a measuring apparatus embodying my invention with the tank portion shown in dotted lines; Fig. 2 represents a side elevation of the apparatus with a portion of the tank 45 broken away to show the interior construction; Fig. 3 represents a section on the line 3^a-3^a of Fig. 1; and Fig. 4 represents a side elevation of a modified form of apparatus, with a portion broken away.

50 1, designating the bed for the apparatus, is provided with two pedestals or supports 2, spaced apart and adapted respectively for receiving the supply pipe 3 through which the water of condensation or any suitable water supply is led to the apparatus, and a discharge or suction pipe 4 connected

to the pump 5. The pedestals 2 also form trunnion bearings for a suitable casting 6 having a head plate 7 secured thereto for supporting the tank 8, so that the latter is 60 suitably supported for tilting action. The tank 8 is divided into two compartments 9 and 10, by a transverse division plate 11 which is arranged in the present instance substantially above the pivot point of the 65 tank and is provided with an opening 12 forming an overflow communication between the two compartments. The casting 6 is provided with two channels 13 and 14, the former of which has communication through 70 the bottom of the tank with the compartment 9 while the latter similarly communicates with the compartment 10. The channel 13 is, furthermore, connected by a flexible conduit 15 with a valve 16 located in the 75 supply pipe 13, this valve 16 being controlled by a lever 17 connected at one end to the valve stem and at the opposite end to a suitable fixture 18 secured to the tank 8 in such a manner as to cause the valve 16 to 80 be either opened or closed as the tank moves from one position to another. The channel 14 is connected by the flexible conduit 19 to the suction pipe 4 and serves to convey the contents of the compartment 10 to the pump 85 and thence to the boiler 20 by way of the pump discharge pipe 21. The pump is operated by steam under pressure supplied by the steam pipe 22, said supply being governed by a valve 23 which is automatically 90 actuated by the pivoted lever 24 from the connection 25 fixed to the tank 8. In connection with the mounting of the tank 8 it will be noted, the division plate 11 is so located that the compartment 10 is longer 95 than the compartment 9, and therefore when it is filled to a certain height, by the water overflowing from the compartment 9, it will overbalance the weight of the contents in the compartment 9 and cause the tank to 100 tilt, thus operating the valves 16 and 23 in the required manner to admit steam to the pump and simultaneously cut off the supply of condensed water. In order to regulate this tilting action and more definitely control the measured quantity of liquid which overbalances the tank, I have provided an adjustable counterweight 26 at the proper end of the tank to vary the action of the tank as desired. 27 designates a registering 105 device suitably fixed adjacent the tank 8 and having an operating arm 28 suitably

connected to the tank or its adjuncts so that each movement of the tank causes the said arm to operate and register every tilting movement of the tank, whereby the total quantity of water discharged may be determined. 29 and 30 designate, respectively, stops located at the respective ends of the tank 8 to limit the tilting action of the tank, the one preferably being shorter than the other for the purpose of permitting proper tilting movement.

It will be observed that the suction pipe 4 to the pump is provided with a valve 33, preferably adjacent to the tank and that this valve is operated by a lever 34 and link 35 having connection with the tank, so that as the tank tilts downward at the right hand end in Fig. 2, the valve 33 will be opened, and this at the same time that the water valve 16 is closed and steam valve 23 is opened. Now, while I prefer to employ this valve 33 in the suction pipe 4 to the pump in all cases, it is not at all essential, especially where the pump is delivering against a relatively high pressure. On the other hand, where the apparatus is delivering against a very low pressure, not exceeding that of the water supply, the use of this valve 33 prevents the water leaving the compartment 10 until the tank has been tilted. In this latter case the valve 33 insures accurate measured quantities of the water to be registered, whereas if there was no valve 33 employed the water pressure in the tank 10 might cause quantities of water to escape through the valves of the pump without being measured and registered. Hence, while I prefer in all cases to provide both valves 23 and 33, the latter may be omitted when desired, namely, in those cases where the discharge pipe 4 has a pressure on its outlet side sufficient to prevent flow of water by gravity or the pressure of the water in compartment 10.

45 In Fig. 4 I have shown a modified construction wherein the compartment 9 is reduced substantially to a conduit constituting a receiving chamber 31. This chamber 31 is substantially an inlet conduit in which the water of condensation passes prior to its discharge into the compartment 10. In this form the counterweight 26 is necessarily heavier than that shown in the preferred form in order to properly counterweight the tank 8. 32 designates an air vent which may be normally open, as will be understood. In this figure I have omitted the valve 33 in the pipe 4, by way of example and as illustrating that in some cases it may be dispensed with.

It will be noted that the compartment 10 in either form of the apparatus is somewhat longer than the compartment 9, so that a normally greater leverage is exerted 65 while receiving water of condensation

whereby the tank will freely tilt to lower the compartment 10 in the desired manner. In the operation of the apparatus it will also be seen that this tilting of the tank alternately opens and closes the valve 16 on the one hand and the valves 23 and 33 on the other. In normal position, as shown in Fig. 2, the valve 16 will be open to admit water of condensation into the compartment 9 either under pressure or by gravity, 75 while the valves 23 and 33 will be closed. The overflow through the opening 12 into the compartment 10 gradually fills this latter compartment to the required level to overbalance the weight of water in compartment 9 plus the counterweight 26, and the tank then automatically tilts and lowers the free end. This action closes the valve 16 to cut off the water supply, but opens the control valve 23 to admit steam to the pump. The pump thereupon comes into action and removes an amount of the collected water in compartment 10 corresponding to the desired measured quantity which is determined by the water content of compartment 9 modified by adjustment of the counterweight 26. Upon the removal of the water from the compartment 10 the tank tilts to its normal position, closing the valves 23 and 33 and opening the valve 16, so that the operation may be repeated. If desired, the counterweight may be omitted, but its use is advantageous when great accuracy is required in having the water measured exactly registered by the registering mechanism 27.

Furthermore, the lowering of the tank to discharging position actuates the registering mechanism 27 so that an accurate register may be kept of the quantity of collected and discharged water.

It will further be apparent, that since all of the parts are proportioned to operate positively in a definite manner and all ports and passages are of comparatively large size, there is practically no possibility of the same clogging or becoming defective in their operation. In addition, it will be noted that I have dispensed with all float mechanism, stuffing boxes, packing or other means which require delicate adjustment or manipulation, and consequently my improved collecting and measuring apparatus is easily installed, easily kept in order, and very positive in operation.

From the foregoing description of the operation of the device it will be seen that the pump is governed to intermittently come into operation and withdraw a quantity of the collected water from the compartment 10. In addition there is also an intermittent actuation of the valves controlling the supply and discharge of the water to and from the tank, so arranged as to entirely cut off the supply when the pump is in operation

and vice versa, thereby making it possible to discharge a measured or definite quantity of the collected water at each operation of the tank and pump. In some cases the 5 pump may be dispensed with, as where the discharge from compartment 10 takes place by gravity, and in such cases the valve 23 would be dispensed with.

It will now be apparent that I have devised a novel and useful construction which 10 embodies the features of advantage enumerated as desirable, and while I have in the present instance shown and described the preferred embodiment thereof which has been found in practice to give satisfactory 15 and reliable results, it is to be understood that I do not restrict myself to the details, as the same are susceptible of modification in various particulars without departing 20 from the spirit or scope of the invention.

Having now described my invention, what I claim as new and desire to protect by Letters Patent is:—

1. In a device of the character stated, the 25 combination of a tank mounted to tilt, a discharge pipe from said tank, a pump having its suction end connected to said discharge pipe, a steam supply pipe for said pump, a valve in said steam pipe, and means 30 operated by said tank for controlling the operation of said valve whereby the operation of said pump is controlled.

2. In a device of the character stated, the 35 combination of a tank mounted to tilt and adapted to be tilted to discharging position by the weight of collected water, means to counterweight said tank in normal or receiving position, a discharge pipe from said tank, a pump having its suction end connected to said discharge pipe, a steam supply pipe for said pump, and means intermittently operated in accordance with conditions within said tank for controlling the supply of steam to said pump.

45 3. In a device of the character stated, the combination of a tank mounted to tilt, a water supply pipe connected to said tank, a valve in said water supply pipe, a discharge pipe connected to said tank, a pump 50 having its suction end connected to said discharge pipe, a steam supply pipe for said pump, a valve in said steam pipe, and means operated by said tank for alternately opening and closing both of said valves, one 55 being open while the other is closed and vice versa, whereby measured quantities of water are intermittently removed from said tank by said pump.

4. In a device of the character stated, the 60 combination of a tank suitably mounted to tilt, said tank divided into two compartments and providing an overflow opening from one compartment to the other, a water supply pipe having communication with one of 65 said compartments, a water discharge pipe

having communication with the other compartment, a pump having its suction end connected to said discharge pipe, a steam supply pipe connected to said pump, and means operated by the tank for respectively 70 controlling the feeding of water through said supply pipe and steam to said pump.

5. In a device of the character stated, the combination of a tank suitably mounted to tilt, said tank divided into two compartments and providing an overflow opening from one compartment to the other, a water supply pipe having communication with one of 75 said compartments, a water discharge pipe having communication with the other compartment, a pump having its suction end connected to said discharge pipe, a steam supply pipe connected to said pump, and means operated by the tank for alternately closing said supply pipe and opening said 80 steam pipe and vice versa, whereby the action of said pump is automatically and intermittently controlled.

6. In a device of the character stated, the combination of a tank suitably mounted to tilt, said tank divided into two compartments and providing an overflow opening from one compartment to the other, a water supply pipe having communication with one of 90 said compartments, a water discharge pipe having communication with the other compartment, a pump having its suction end connected to said discharge pipe, a steam supply pipe connected to said pump, means operated by the tank to close the 95 supply pipe and open the steam supply pipe and vice versa, whereby said pump is automatically and intermittently operated, and means to register the oscillations of the tank.

7. In a device of the character stated, the combination of a tank suitably mounted to tilt, said tank divided into two compartments and providing an overflow opening from one compartment to the other, a water 100 supply pipe having communication with one of said compartments, a water discharge pipe having communication with the other compartment, a valve for controlling the supply of water through said supply pipe, 110 means for controlling the flow of water through the discharge pipe, a steam pipe for supplying steam to operate said means, a valve in said steam pipe controlling the supply of steam, and operating connections 115 between each of said valves and said tank whereby tilting movement of said tank operates said valves intermittently.

8. In a device of the character stated, the combination of a tank mounted to tilt, a 125 discharge pipe for the tank having a valve therein, a supply pipe for the tank also having a valve therein, a steam actuated means in connection with the discharge pipe, a steam pipe to supply steam to the steam 130

actuated means, a valve in the steam pipe, and connections between the tank and the several valves for opening the valve in the supply pipe and closing the valves in the steam pipe and discharge pipe, and vice versa, by the oscillations of the tank.

9. In a device of the character stated, the combination of a tank mounted to tilt, a discharge pipe for the tank having a valve therein, a supply pipe for the tank also having a valve therein, a steam actuated means in connection with the discharge pipe, a steam pipe to supply steam to the steam actuated means, a valve in the steam pipe, connections between the tank and the several valves for opening the valve in the supply pipe and closing the valves in the steam pipe and discharge pipe, and vice versa, by the oscillations of the tank, and means for registering the number of oscillations of the tank.

10. In a device of the character stated, the combination of a tank mounted to tilt and provided with two compartments in communication at their upper part, said compartments being respectively upon opposite sides of the pivotal support of the tank, a supply pipe having a flexible connection communicating with one of the compartments, a discharge pipe having a flexible connection with the other of the compartments, a valve in the supply pipe, a valve in the discharge pipe, connections between the tank and the valves whereby the valves are opened and closed alternately by the tilting of the tank, and means whose operation is intermittently controlled by the tilting of the tank for controlling the flow of water from the discharge pipe when the discharge valve is opened.

11. In a device of the character stated, the combination of a tank mounted to tilt and provided with two compartments in communication at their upper part, said compartments being respectively upon opposite sides of the pivotal support of the tank, a supply pipe having a flexible connection communicating with one of the compartments, a discharge pipe having a flexible connection with the other of the compartments, a valve in the supply pipe, a valve in the discharge pipe, and connections between the tank and the valves whereby the valves are opened and closed alternately by the tilting of the tank.

12. In a device of the character stated, the combination of a tank mounted to tilt and provided with two compartments in communication at their upper part, said compartments being respectively upon opposite sides of the pivotal support of the tank, a supply pipe having a flexible connection communicating with one of the compartments, a discharge pipe having a flexible connection with the other of the compartments, a valve in the supply pipe, a valve in the discharge pipe, connections between the tank and the valves whereby the valves are opened and closed alternately by the tilting of the tank, and means whose operation is intermittently controlled by the tilting of the tank for controlling the flow of water from the discharge pipe when the discharge valve is opened.

In testimony of which invention, I hereunto set my hand.

FREDERICK C. FARNSWORTH.
